CLAIM

The ornamental design for a reclosable top for a container, as shown and described.

DESCRIPTION

FIG. 1 is an isometric view of a reclosable top for a container, showing our new design;

FIG. 2 is a top plan view thereof;

FIG. 3 is a bottom plan view thereof;

FIG. 4 is a left or right elevational view thereof

FIG. 5 is a front or rear elevational view thereof; and,

FIG. 6 is a cross-sectional view taken along line 6-6 of FIG. 2.
